CLAIM

The ornamental design for a chair, as shown and described.

DESCRIPTION

FIG. 1 is a front perspective view of a chair; FIG. 2 is a rear perspective view of the chair shown in FIG. 1;

FIG. 3 is a right side view of the chair shown in FIG. 1;

FIG. 4 is a left side view of the chair shown in FIG. 1;

FIG. 5 is front view of the chair shown in FIG. 1;

FIG. 6 is a rear view of the chair shown in FIG. 1;

FIG. 7 is a top view of the chair shown in FIG. 1; and,

FIG. 8 is a bottom view of the chair shown in FIG. 1.

The broken lines showing the base and the controls in FIGS. 1-8 are directed to environment and are for illustrative purposes only; the broken lines form no part of the claimed design.

1 Claim, 8 Drawing Sheets
